DRAFTING APPARATUS

George E. Repass, Gulfport, Miss.

Application July 16, 1934, Serial No. 735,466

9 Claims. (Cl. 19—154)

This invention relates to an improvement in the processing and drafting of roving and yarn. The invention relates to the problem of controlling the fibers while drafting from a large or coarse 5 roving down to a fine roving or yarn. The revolving trumpet embodying this invention will be placed between the rolls to control the fibers.

The first object of this invention is to line up the floating fibers which have a tendency to 10 spread and get out of their regular channel while passing from one roll to another.

A second object of the invention is to condense the fibers while passing from one roll to another, in order that each succeeding roll can 15 draw them out into an even finer roving or yarn.

A third object of the invention is to make it possible to have a continued drafting of several sets of rolls in the same machine so that real heavy roving can be drafted into very fine roving or yarn in one process.

20 A fourth object of this invention is to twist or roll the fibers together while passing from one roll to another.

A fifth object of this invention is to twist or 25 roll the fibers together to make them draw evenly while being drafted from one roll to another.

A sixth object of this invention is to line up and control short fibers and loose lint and thereby keeping loose lint from flying about on the 30 frames.

A seventh object of the invention is to cause fibers to close up from a flat strand to a compact round one.

It is customary in the textile work to have three 35 rolls on the roving frame which are known as front, middle and back rolls, thereby accomplishing about 1.20 draft between the middle and back rolls, which is usually known as the brake draft, the main drafting being done between the front 40 and middle roll, which usually runs from 3 to 6 draft. The system used on spinning frames is practically the same as on roving frames. It is not customary to have too long a draft on roving or spinning frames, as the fibers spread out too 45 much causing uneven work, although on the spinning frame the draft between the front and middle rolls is as high as from 5 to 12.

These objections and troubles are overcome by the use of the present invention which embodies 50 a revolving trumpet placed either between the drafting rolls or between rolls with a small amount of drafting and which trumpet or a series of trumpets placed between different rolls accomplishes the foregoing objects of the invention.

In the accompanying drawings,

Fig. 1 is a diagrammatic plan view of a portion of drafting apparatus showing the application of the invention to a three-roll system;

Fig. 2 is a vertical sectional view on the line 5 2—2, of Fig. 1;

Fig. 3 is a similar view at right angles thereto, on the line 3—3, of Fig. 1;

Fig. 4 is a view similar to Fig. 1, but showing the application of the invention to a four-roll system;

Fig. 5 is a similar view showing two trumpets in the system;

Fig. 6 is a perspective view of a portion of the trumpet bar and a trumpet therein; and

Fig. 7 is a view similar to Fig. 1 but showing the invention applied to a five-roll system.

For convenience, only a portion of the usual drafting frame is shown, sufficient to illustrate the application of the invention thereto, but it 20 will be understood that the invention may be applied to each strand of roving or yarn passing through the drafting rolls and that the invention is applicable to different roll systems with which it may be used as found desirable.

In Fig. 1, I have shown a three-roll system in which a portion of the frame is designated 1, and in which frame are the back, middle, and front rolls 2, 3 and 4, respectively, each of which is really a pair of rolls between which the strand 30 of roving or yarn passes. The strand is designated S, and passes through the usual roving guide 5, being flattened out into a ribbon between the back and middle rolls 2 and 3. Mounted between the middle and front rolls 3 and 4 is my 35 revolving trumpet designated generally by the numeral 6, and which is shown in section in Fig. 3 of the drawings.

A trumpet bar is designated by the numeral 7, and is shown mounted between the middle and 40 front rolls 3 and 4, respectively, being constructed hollow to serve as a suitable holder or guide for the trumpets. The trumpet bar extends throughout the length of the drafting frame and has one trumpet for each strand of roving or yarn, 45 passing through the drafting rolls.

As shown in Fig. 3, each trumpet 6 has a tubular body portion 8 journaled in opposite sides of the trumpet bar 7, and through which a central opening 9 extends being either straight 50 or preferably tapered with a larger receiving end than the delivering end so as to compress and condense the fibers passing therethrough. This opening 9 may be made perfectly smooth on the inside or it may be made with a straight or worm 55

groove therein, as desired. The trumpet 6 is formed with a peripheral enlargement 10, having a V-shaped groove 11 therein, to receive a cord 12, which extends on opposite sides thereof for 5 rotating the trumpet. The cord 12 extends through the trumpet bar for driving the trumpets mounted therein and may be crossed between adjacent trumpets. The location of the cord inside the trumpet bar protects it against accident 10 dental displacement. The cord is driven from a pulley 13, mounted on a shaft 14, journaled in a bearing 15, carried by the drafting frame. The shaft 14 may be driven in any desired manner, it being driven through gearing 16 from the 15 front roll 4, according to the illustration shown in Fig. 1. Instead of driving the trumpets by means of the cord illustrated, they might be driven by a chain, if sprocket teeth should be provided on the peripheral enlargement 10, or the 20 trumpet might be driven from a worm running through the trumpet bar 7 and geared to the peripheral enlargement 10. Any suitable manner of driving the trumpet may be used as found desirable. The speed of the trumpet may be regulated to suit the particular work desired.

While the strand S, is flattened out into ribbon shape between the back and middle rolls 2 and 3, the trumpet 6 compresses this strand into a round compact strand while it is being drafted 30 from the middle to the front roll, getting a draft from 3 to 12, as may be desired. This draft may be accomplished by the use of the trumpet on the roving or spinning frame.

Fig. 4 shows a four-roll system showing draft of from 3 to 6 between the back and third rolls 35 20 and 21, respectively, showing the fibers being flattened out in a ribbon-like strand. The trumpet 6a is placed between the third and second rolls, the latter being designated 22, for the purpose of condensing the fibers from a flat strand to a round compact one, which is received by 40 the roll 22, and from which the strand passes to the front roll 23. In this instance, the main purpose is to condense the fibers while obtaining only a small draft of about 1.25 to 1.50 getting 45 the fibers into good shape to be drawn between the second and front rolls, obtaining a draft here of about from 3 to 12. The system shown in Fig. 4 can produce a draft of from 5 to 8, depending largely upon the class of stock being used.

Fig. 5 shows a four-roll system drafting all rolls getting a total of between 27 and 220 depending upon the type of stock used. In this arrangement in addition to the trumpet 6a, between the rolls 21 and 22, a second trumpet 6b is used between the second and front rolls 22 and 23, which have a tendency to continue to condense the fibers into smaller strands.

Fig. 7 shows a five-roll system which is very suitable for long staple cotton. This system operates very similar to that shown in Fig. 5, except that in this instance the second roll 33 is a very small roll and is known as a slip-draft roll. In this system, the drafting between the back and fourth rolls 30 and 31, and also between the fourth and third rolls 31 and 32, is practically the same as in Fig. 5. There is very little draft between the third and second rolls 32 and 33, which space is used to condense the fibers into a round strand. Drafting again takes place between the second and front rolls 33 and 34. The second top roll is a very light roll which allows the long fibers to slide through without breaking them.

With the use of a number of rolls and these revolving trumpets, it is possible to spin fine yarn from a single strand of drawing sliver, however, it is better to use two strands of roving because if one should run out or break back, the broken one could be pieced back to the remaining one, thereby saving a re-threading operation.

I claim:

1. In drafting apparatus, the combination with a plurality of drafting rolls, of a tubular trumpet 10 bar located between adjacent rolls, trumpets each having opposite ends thereof journaled in opposite sides of said trumpet bar and having a tapered opening therethrough, and means extending longitudinally through the trumpet bar and having driving engagement with said trumpets for rotating said trumpets.

2. In drafting apparatus, the combination with a plurality of drafting rolls for drafting a strand passing therethrough, of a tubular trumpet bar 20 located between adjacent rolls and extending parallel therewith, a tubular trumpet mainly housed within and protected by the trumpet bar and journaled in opposite sides of said trumpet bar, said trumpet having a tapered opening there-through in alignment with the drafting rolls for compacting and condensing the fibers in passing between the rolls, and means extending through and protected by the trumpet bar for rotating the trumpet.

3. In drafting apparatus, a hollow trumpet bar, trumpets within said hollow trumpet bar, each of said trumpets having a tubular body portion journaled in opposite sides of said trumpet bar and having a conical opening therethrough for compacting and condensing the fibers of a strand passing therethrough, and means extending through the trumpet bar having driving engagement with the trumpets for rotating the same.

4. In drafting apparatus, a hollow trumpet bar, 40 trumpets housed within said bar, each of said trumpets having a tubular body portion journaled in opposite sides of said trumpet bar and having a tapered opening therethrough for compacting and condensing the fibers of a strand passing 45 therethrough, and means housed within the trumpet bar having driving engagement with the peripheries of said trumpets for rotating the same.

5. In drafting apparatus, the combination with 50 a plurality of drafting rolls for receiving and drafting a strand, of a hollow trumpet bar extending longitudinally of said rolls, a trumpet having opposite ends journaled in opposite sides of said trumpet bar, a drive shaft extending 55 transversely relative to the rolls, and a belt extending longitudinally through the trumpet bar and having driving engagement with the trumpet and drive shaft for driving the trumpet therefrom.

6. In drafting apparatus, the combination with a plurality of drafting rolls for receiving and drafting a strand, of a hollow trumpet bar extending longitudinally of said rolls, a plurality of trumpets journaled in said trumpet bar in 65 spaced relation, a drive shaft extending transversely of the trumpet bar adjacent an end thereof, and a belt extending longitudinally through the trumpet bar and around the drive shaft and trumpets in driving engagement therewith.

7. In drafting apparatus, the combination with a plurality of drafting rolls for receiving and drafting a strand, of a hollow trumpet bar extending longitudinally of said rolls, a plurality of trumpets each having opposite ends journaled 75

in opposite sides of said trumpet bar, a drive shaft extending transversely of the trumpet bar adjacent an end thereof, and a belt extending longitudinally through the trumpet bar and around the drive shaft and trumpets in driving engagement therewith, said belt being crossed between adjacent trumpets and between the drive shaft and adjacent trumpet.

8. In cotton drafting apparatus, the combination of a plurality of pairs of cotton drafting rolls, said pairs of rolls being arranged relatively close together and in parallel relation, said drafting rolls being constructed and arranged for drafting cotton rovings at a plurality of different points therealong, a hollow trumpet bar extending longitudinally between the pairs of rolls, a plurality of short rotary trumpets journaled in said trumpet bar at the respective points of

drafting, and means extending lengthwise through said trumpet bar for driving the trumpets.

9. In cotton drafting apparatus, the combination of a plurality of pairs of cotton drafting rolls, said pairs of rolls being arranged relatively close together and in parallel relation, said drafting rolls being constructed and arranged for drafting cotton rovings at a plurality of different points therealong, a hollow trumpet bar made in two sections divided longitudinally and secured together, said trumpet bar extending longitudinally between the pairs of rolls, a plurality of short rotary trumpets journaled in opposite sides of said trumpet bar at the respective points of drafting, and means extending lengthwise through said trumpet bar for driving the trumpets.

GEORGE E. REPASS.
